PATRICK HENRY GRIFFIN, OF NEW YORK, N. Y., ASSIGNOR OF ONE-FOURTH TO HENRY H. VAUGHAN, OF MONTREAL, QUEBEC, CANADA.

CASTING APPARATUS.

1,281,946.

Specification of Letters Patent.

Patented Oct. 15, 1918.

Application filed April 27, 1914, Serial No. 834,762. Renewed June 17, 1918. Serial No. 240,526.

To all whom it may concern:

Be it known that I, PATRICK HENRY GRIFFIN, a citizen of the United States of America, residing in the city of New York, State of New York, United States of America, have invented certain new and useful Improvements in Casting Apparatus; and I do hereby declare that the following is a full, clear, and exact description of the same.

In the practice heretofore and now carried on for the manufacture of cast iron car wheels and other products made in foundries, a serious disadvantage results from the fact that the operation is carried on in more or less crude manner and subject to the variations in section and mechanical conditions of the product and to certain imperfections and defects that arise from the means and materials used and the apparatus in vogue. Another disadvantage arises from the lack of proper control of the cooling of the different parts of such castings and from undue shrinkage strains, cracks and other defects that develop from such lack of control.

Another disadvantage results from the fact that labor and supervision properly skilled in the art of preparing car wheel molds and carrying on the operation in all stages, is difficult to obtain and that the whole order of the operation has fallen into a low and dangerous state for that reason.

To obviate these and other disadvantages and to reliably improve the quality of the product is the object of this invention which consists of new and improved method and means of doing the work, simplifying the same and making it possible for anyone possessed of ordinary mechanical skill to assemble the various parts of the apparatus and to make and prepare certain parts of the same as required, and to complete the operation with greater certainty of securing products of a high and uniform order of quality and mechanical conditions.

My invention consists of a casting apparatus consisting of members that replace the members or parts of the flask or mold used for making car wheels and like castings as well as the kind of material used therein, replacing them with new members and forms of material that insure more reliable and improved results as described herein; and in the construction, combination and particular

arrangement of parts hereinafter illustrated and described. The method also forms part of my invention.

While the essential principle of this invention is to provide the new means and apparatus as herein described for the purpose stated, the product produced by such method and apparatus constitutes a new quality and type of car wheel and forms the subject-matter of a separate invention.

For full comprehension, however, of my invention reference must be had to the accompanying drawings forming a part of this specification, in which similar reference characters indicate the same parts, and wherein:

Figure 1 is a vertical diametrical sectional view illustrating my improved casting apparatus;

Figs. 2 and 3 are similar sectional views of the means whereby the cores for use in the casting apparatus are manufactured;

Fig. 4 is a similar sectional view of the casting apparatus partly dismembered as required for cooling the cast article; and

Fig. 5 is a similar view illustrating the use of co-acting parts of the apparatus in connection with a cooling box.

My improved apparatus comprises a chill consisting of two engaging members, a bottom plate member, an annular top plate member, central annular bottom and top plate members and previously manufactured cores, the chill indicated at D consisting of a relatively flat annular plate the upper face D¹ of which presents a matrix formation suitable to cast a flange on the wheel such chill D having an inwardly projecting beveled flange D², the outer portion near the outer periphery being recessed. The bottom plate member B is of annular form having beveled periphery B' and being of a diameter to fit within the chill D and rest upon the flange D² while the inner edge thereof has a beveled face B² and its underside perforated lugs B³ the center ring b fitting within the bottom plate member B and having its periphery beveled as at b¹ to rest upon the beveled face B². The chill C is of cylindrical form and stands substantially at right angles to the chill member D, one edge thereof being beveled as at C' with which the beveled edge A' of the top plate member A engages and upon which it rests when the apparatus is being assembled for a cast. This

top plate member is secured in position by a series of wedges g' . A pouring head a of tubular form is provided with a beveled face a' engaging a beveled face A^2 presented by the top plate member. This pouring head is secured in position by wedges g^2 , g^3 and lugs j . Gas vents 25 are provided in the top and bottom plate members A and B. These parts of the apparatus carry the cores which are previously manufactured from dry sand mixed with a suitable binder or filler to enable the same to be handled without damage. These cores are usually of annular form and are indicated at e' , e^2 , and e^3 respectively and the pouring head member of annular cross-section indicated at e^4 and the center e^5 are made from the same material.

The method by which these cores are manufactured is well-known to those skilled in the use of dry sand cores for molding.

The cores and matrix faces of the chills are preferably formed to meet Master Car Builders' requirements. Chaplets h and m are employed for retaining the cores e^2 and e^3 in position. Grappling tongs of any approved construction are indicated at D^4 and a cooling box at H . This cooling box is provided with a central opening H' and beveled lugs H^2 while the wedges H^3 are adapted to center the bottom plate member in the box which also has a vertical inclosing wall H^5 .

My improved method is preferably as follows:—

The chill D (see Fig. 1) is placed in horizontal position and the plate B is placed in same. The latter centers itself by means of the machine beveled faces D^2 and B' . The core e' is placed in position upon the plate B as indicated in Fig. 1, the chaplets m serving to retain both cores e' and e^3 in place.

The center ring b which contains the dry sand center e^5 is placed in position as shown and centers itself by means of the machine beveled faces B^2 and b' .

The center ring core e^3 is placed in position as shown and secured by the chaplets.

The center core e^5 is then located in position as shown in Fig. 1.

The chill member C is inverted and the plate A is placed in position therein and centers itself by means of the machine beveled faces A' and C' . It is secured and held in position firmly by the wedges g' .

The core e^2 is placed in the inverted top plate member A and secured by the chaplets h , and the chill member C with top plate member and core e^2 are then turned back. The pouring head a containing the dry sand core e^4 is then placed in position in the top plate member as shown and centers itself by means of the machine beveled faces a' and A^2 . It is secured in position and held firmly by the wedges g^2 placed under the lugs j .

The parts C and D are then closed together and form with the other parts associ-

ated with them as described, a complete mold or form for casting the molten metal into. They are secured together by clamps or ordinary devices of the kind and the metal is cast.

The gases formed in the process of casting 70 are conducted freely from the apparatus or mold, by means of the usual vents and openings 25 for same in plates A and B.

As soon as the molten metal in the pouring head a has solidified sufficiently to admit 75 of so doing the wedges g^2 and the pouring head a are removed.

The chaplet h is disconnected from the plate A and the latter with the chill C are removed, thus exposing the surface of wheel 80 tread and upper surface of flange.

The core e^2 remains undisturbed on the casting and protects it from cooling as desired.

The center core e^5 which is formed with a 85 central opening or recess e^6 , as shown, is driven through the opening in center of plate B by striking it with an iron bar, the fact that there is nothing but sand to break through making the removal an easy matter. 90

A central opening is thus left in the casting through which cold air may circulate as desired and cool the center of casting at the rate desired. By partly closing such opening, if desired, the rate of cooling may be 95 retarded.

After these steps of the operation have been carried out, the plate B with the casting on same is ready for removal to the cooling point.

See Fig. 4 which shows the plate B with wheel casting on same after the above described operations have been carried out and before the wheel is placed in the cooling part 100 of the apparatus.

Fig. 5. The plate B is lifted out of the chill D by the grappling tongs D^4 or the removal is accomplished in any other convenient way, and the cooling box H is placed under the plate B and the latter is lowered 110 and centers itself in the cooling box by means of the machine beveled lugs H^2 and B^3 and is secured in position by the wedges H^3 .

Dry sand or any other suitable or desired 115 insulating material is placed in the space H^4 between the tread and flange of car wheel and wall of the box to retard cooling or control the same at any desired rate.

After being allowed to remain in this box 120 for about twenty-four hours the cast wheel is ready for use.

What I claim is as follows:—

1. A casting apparatus for casting chilled car wheels or the like comprising a bottom plate and cores, a supporting ring for said bottom plate for imparting form to a part 125 of the wheel flange, a pouring head, a center ring, a chill ring for imparting form to the face of the tread and a top plate supported 130

by the chill ring, said pouring head member and center ring being in the top and bottom plates respectively and a center core movable without injuring or disturbing the metal in the casting.

2. A casting apparatus for casting chilled car wheels or the like comprising a bottom plate and cores, a supporting ring for said bottom plate and for imparting form to a portion of the wheel flange, a pouring head, a center ring, a chill ring, for imparting form to a face of a wheel tread and a top plate supported by the chill ring, and said pouring head member and center ring distinct from and fitting in the top and bottom plates respectively and a center core removable without injuring or disturbing the metal in the casting.

3. A casting apparatus consisting of two members or chills, annular plates, each of the said members or chills being adapted to receive one of the said annular plates, rings, said annular plates having central openings adapted to receive the said rings, cores, means securing said cores to the annular plates and rings, means permitting the removal of said cores and rings quickly after the molten metal solidifies or partly solidifies in part of such castings, for the purpose of permitting the quick control and regulation of temperature in the center or other parts of such castings without disturbing or injuring the metal in other parts or the casting as a whole or losing control of the temperature of same, means effecting detachable connections between the parts of such apparatus.

4. In a casting apparatus the combination with annular top and bottom plate members of dish form, annular displaceable cores carried within such members, an annular core carried by the bottom member and

in fixed relation with the core of the latter, a center ring engaging and supported by the bottom member, a tubular pouring head 45 engaging and supported by the top member, a substantially flat annular chill engaged by and supporting one edge of the bottom member, a substantially cylindrical chill engaging and supported by the said substantially flat chill, and means securing the cores in position.

5. In a casting apparatus the combination with annular members corresponding to the usual top and bottom plate members, annular displaceable cores carried within such members, an annular core carried by the bottom member and in fixed relation with the core in the latter, a ring, said annular core being engaged and supported by said ring 60 which is engaged and supported by the bottom plate member, a tubular core, a tubular pouring head-ring engaging and supporting the tubular core, said head-ring being engaged and supported by the top plate member, a substantially cylindrical chill member engaged by and supporting one edge of the top plate member, a substantially flat annular chill engaging and supporting the substantially cylindrical chill member, and 65 means securing such members and cores in position and permitting the removal of all or parts of the same at will without disturbance to or injury of other parts of the casting or article made and the control of the 70 temperature in parts or in all of such castings or articles.

In testimony whereof I have signed my name to this specification in the presence of two witnesses.

PATRICK HENRY GRIFFIN.
